UNITED STATES PATENT OFFICE

WALTER S. ADAMS, OF PHILADELPHIA, PENNSYLVANIA, AND EUGENE SLINGLUFF, SR., OF CLEVELAND HEIGHTS, OHIO, ASSIGNEES TO THE J. G. BRILL COMPANY, OF PHILADELPHIA, PENNSYLVANIA, A CORPORATION OF PENNSYLVANIA

HIGH-SPEED ARTICULATED CAR

Application filed September 10, 1929. Serial No. 391,633.

This invention relates to vestibule mountings for articulated cars.

An important object of the invention is to provide in a construction of this character an arrangement permitting the vestibule to be held against rotation with relation to the truck and at the same time permitting the necessary oscillation of this vestibule to accommodate shifting movements of the cars which it connects.

A further object of the invention is the production of a structure of this character which will permit the vestibule to be directly bolted to the truck and held against vertical displacement with relation thereto and at the same time be capable of the necessary oscillatory movements.

A further object of the invention is the production in a construction of this character of an arrangement whereby the cushioning means for the vestibule, which maintains the vestibule in its normal position and returns it to such normal position after displacement, may be carried by the platforms of the cars which the vestibule connects.

A still further object of the invention is the production of apparatus of this character which may be very readily assembled and which will be durable and efficient in service.

These and other objects we attain by the construction shown in the accompanying drawings wherein, for the purpose of illustration, we have shown a preferred embodiment of our invention and wherein:

Fig. 1 is a horizontal sectional view through a vestibule mounting constructed in accordance with our invention;

Fig. 2 is a vertical sectional view therethrough on line 2—2 of Fig. 1; and

Fig. 3 is a partially diagrammatic view showing the drum mounting in use between two cars.

Referring now more particularly to the drawings, the numeral 10 generally designates the truck bolster upon which is seated a car-supporting pivot structure 11 supporting the adjacent ends of cars 12. This supporting structure is substantially identical to that illustrated in the copending application of Walter S. Adams and Elmer Latshaw for

patent on vestibule mountings for high speed articulating cars filed August 28, 1929, Serial No. 389,004, now Patent No. 1,751,300, granted March 18, 1930, including a supporting plate 13 having an upwardly projecting confining rim or retaining flange 14 and a centrally disposed upwardly projecting hub-forming flange 15. Between the retaining and hub flanges 14 and 15 are disposed pivot blocks 16 having sockets 17 for the reception of socket-engaging elements 18 carried by the car. The upper end of the hub flange 15 is key-notched as indicated at 19 for the reception of dentations 20 formed upon the lower end of the bolt guide 21 which projects downwardly from a casting 22 rigidly secured to the bottom of vestibule 23 at the axis thereof.

The bolt guide 21 has a bore 22^a for the reception of king bolt 25, the upper end of this bore terminating in a polygonal socket for the reception of the head 26 of the bolt. Beneath the truck bolster the king bolt 25 is surrounded by a spring 27 which acts to prevent vertical displacement of the bolt and, accordingly, to prevent vertical displacement of the vestibule 23 and disengagement of dentations 20 from the notches 19.

The car platforms which are supported from the structure 11 are formed in their upper surface with sockets 28 receiving springs 29 bearing against the under surface of the vestibule floor through wear plates 30. These springs 29 are under compression to support the load of vestibule 23 and any added passenger load and being spaced from the axis of the vestibule will act at all times to maintain the vestibule in its normal position while yielding to permit movement of the vestibule to accommodate relative movements of cars 12. The king bolt-receiving bores of the truck bolster, casting and hub flange 15 loosely receive the king bolt so that the upper end of this hub flange operates as a pivot about which the vestibule may rock. A structure of this character permits use of the weather strip tensioning springs 31 at the under surface of the vestibule floor as illustrated and described in the copending application above identified.

It will be obvious that with a structure of this character the vestibule will at all times move with the truck and be maintained in a predetermined alignment therewith and thus be maintained in the best possible position for alignment with the car bodies.

As the structure employed is obviously capable of a certain range and change of modification without materially departing from the spirit of our invention, we do not wish to be understood as limiting ourselves thereto except as hereinafter claimed.

We claim:

1. In combination with adjacent car ends supported from a common truck, a drum vestibule, connections between the drum and truck limiting separation of the drum and truck while permitting oscillation of the drum and springs extending between the upper surfaces of said car ends and the bottom of said drum.

2. In combination with adjacent car ends, a truck, a bearing element mounted upon the truck including an annular bearing groove and a central hub, bearings for said car ends oscillatable in the bearing groove, a vestibule drum extending over the adjacent car ends and having at its center a support engaging the hub of the bearing element, means preventing separation of said support and bearing element and springs extending between the car ends and the bottom of the drum.

3. In combination with adjacent car ends, a truck, a bearing element mounted upon the truck including an annular bearing groove and a central hub, bearings for said car ends oscillatable in the bearing groove, a vestibule drum extending over the adjacent car ends and having at its center a support engaging the hub of the bearing element, and means preventing separation of said support and bearing element and springs extending between the car ends and the bottom of the drum, the bearing element and support having engagement with one another permitting oscillation of the support while preventing rotation thereof.

4. In combination with adjacent car ends supported from a common truck, a drum vestibule, connections between the drum and truck limiting separation of the drum and truck while permitting oscillation of the drum, springs extending between the upper surfaces of said car ends and the bottom of said drum, and aligned elements carried by the drum and truck and disposed axially of the drum, said elements having engagement with one another preventing rotation of the drum with relation to the truck.

5. In combination with adjacent car ends and a common truck for supporting the same, means defining an annular bearing groove at the center of the truck, bearing elements oscillatable in said groove and with which the car ends engage, said means including a hub

portion, a drum axially supported from said hub portion and extending over the car ends, means preventing separation of the drum and said hub portion and springs extending between the car ends and the bottom of the drum.

6. In combination with adjacent car ends and a common truck for supporting the same, means defining an annular bearing groove at the center of the truck, bearing elements oscillatable in said groove and with which the car ends engage, said means including a hub portion, a drum axially supported from said hub portion and extending over the car ends, means preventing separation of the drum and said hub portion and springs extending between the car ends and the bottom of the drum, said supporting means and hub portion having engagement with one another preventing relative rotation thereof while permitting a limited oscillation of the drum.

7. In combination with adjacent car ends supported from a common truck, a drum vestibule, connections between the drum and truck engaging the drum axially and limiting separation of the drum and truck while permitting oscillation of the drum, sockets in the upper surfaces of the car ends and underlying the bottom of the drum and springs in said sockets and engaging the bottom of the drum.

8. In combination with adjacent car ends, a truck, a bearing element mounted upon the truck including an annular bearing groove and a central hub, bearings for said car ends oscillatable in the bearing groove, a vestibule drum extending over the adjacent car ends and having at its center a support engaging the hub of the bearing element, means preventing separation of said support and bearing element and springs extending between the car ends and the bottom of the drum, one of said hubs and support having teeth, the other thereof having notches for the reception of said teeth.

9. In combination with adjacent car ends, a truck, a bearing element mounted upon the truck including an annular bearing groove and a central hub, bearings for said car ends oscillatable in the bearing groove, a vestibule drum extending over the adjacent car ends and having at its center a casting provided with an axially-extending tubular support engaging the hub of the bearing element with its lower end, a king bolt extending through an element of the truck, the bearing element and said tubular support and springs extending between the car ends and the bottom of the drum.

10. In combination with adjacent car ends, a truck, a bearing element mounted upon the truck including an annular bearing groove and a central hub, bearings for said car ends oscillatable in the bearing groove, a vestibule drum extending over the adjacent car ends

and having at its center a casting provided with an axially-extending tubular support engaging the hub of the bearing element with its lower end, a king bolt extending through 5 an element of the truck, the bearing element and said tubular support and springs extending between the car ends and the bottom of the drum, said support having teeth upon its lower end, the hub having notches for the 10 reception of the teeth, the bores of the hub and bearing element permitting limited oscillation of the king bolt.

11. In combination with adjacent car ends supported from a common truck, a drum vestibule arranged above said ends and means 15 axially supporting the drums from the truck.

12. In combination with adjacent car ends supported from a common truck, a drum vestibule arranged above said ends and means 20 axially supporting the drum from the truck, said means being held against rotation with relation to both the drum and truck.

13. In combination with adjacent car ends, a truck having a bearing groove to receive, 25 bearing elements projecting downwardly from said car ends, said means affording a hub, a vestibule arranged above the car ends and having an axially disposed depending element seated upon and supported by said 30 hub.

14. In combination with adjacent car ends, a truck having a bearing groove to receive bearing elements projecting downwardly from said car ends, said means affording a 35 hub, a vestibule arranged above the car ends and having an axially disposed depending element seated upon and supported by said hub, one of said hubs and depending portion having teeth, the other thereof having notches 40 for the reception of said teeth.

15. In combination with adjacent car ends, a truck having a bearing groove to receive bearing elements projecting downwardly from said car ends, said means affording a 45 hub, a vestibule arranged above the car ends and having an axially disposed depending element seated upon and supported by said hub, one of said hubs and depending portion having teeth, the other thereof having notches 50 for the reception of said teeth, a bolt extending through said depending portion, the bearing element, and the truck, and a spring urging said bolt downwardly.

WALTER S. ADAMS.
